CONSTRUCTION OF STOVES

Edgar N. Dollin, Long Island, and Benson F. Wad-dell, Jackson Heights, N. Y., assignor to Na-tional Gas Range Corporation, New York, N. Y., a corporation of New York

Application January 11, 1933. Serial No. 651,098

9 Claims. (Cl. 126—39)

This invention relates to improvements in the construction of the front frame for the so-called cabinet type of gas ranges, being specifically directed to a novel form of frame which will afford protection to the vitreous enamelled sheets forming the body and doors of the gas range and at the same time eliminating the necessity of vitreous enamelling the frame itself, while at the same time providing for the artistic treatment of the complete gas range.

Further, it is an object of this invention to provide at a minimum of cost a steel frame of durability and rigidity adapted to cover the edges of the side and the top sheets of the gas range, thus permitting assembly with concealed bolts and further providing for a frame which maintains the oven linings in position while protecting the edges thereof.

In the design and construction of gas ranges, the front frame from time immemorial has presented specific difficulties with respect to its structural aesthetic and utilitarian features. Cast frames which have been used were expensive and liable to warp or be broken, while at the same time presenting the difficulty of properly enamelling the same in mass production. Pressed steel frames require expensive dies in the production thereof and expose fragile surfaces at joints and corners which become affected either in shipping or in use. Structural steel frames as heretofore known present a crude appearance in conjunction with the enamelled sheets forming the top, sides and doors, therefore preventing an artistic appearance.

The present invention contemplates a front frame surrounding the oven and broiler compartments, constructed of angle or L-shaped sections, in each of which one flange lies in the common plane parallel to the front of the range. By means of this arrangement, in conjunction with the doors of the various compartments, oven or broiler sections, there is visible when the doors are closed only a thin bead comprising the edges of the respective angle sections which extend across and along the various door sections.

In this manner, the only portion of the frame that is visible is a bead at the top and sides of the stove having very little surface, which can be finished in ordinary black Japan but will not detract from the appearance of the vitreous enamelled door sections and sheet sections contained within or disposed adjacent said frame and will protect the enamelled sides and top,

while at the same time providing for a contrast to offset and accentuate the enamelled parts. In this manner the cost and difficulty of enamelling of the frame is eliminated and the artistic treatment of the front of the range is simplified.

These and other advantages, capabilities and features of the invention will appear from the subjoined detailed description of one specific embodiment therefor illustrated in the accompanying drawing, in which

Figure 1 represents a perspective view of a stove incorporating the frame.

Figure 2 is a perspective view showing the frame alone.

Figure 3 is a plan view in section showing the relationship of the sides of the oven compartment with respect to the frame.

Referring to the reference characters in the drawing, numeral 10 represents the base frame for the stove, numeral 11 represents the frame for the open burner and numeral 12 represents the front frame for the oven and broiler compartments, the open burner frame 11 being supported on the base frame 10 by means of up-standing brackets 13 resting on the horizontal flange 14 of the base frame, and the front frame 12 for the oven and broiler compartments being bolted at the base of the sides 15 thereof along the horizontal flange 14 of the base frame.

The base frame, the open burner frame, and the front frame for the oven and broiler compartments are formed of pressed steel and although they are shown each as integral shaped members, it is within the province of this invention to build up each of these members by means of separate angle bars.

Referring in detail to the front frame 12 for the oven and broiler compartments, the side members 15 thereof comprise angle bars, likewise the top member 16, the respective side members having front faces 17 and the top member having front face 18 all in the same plane, and the side members have right angular rearwardly extending flanges 19 disposed in planes near the center of the compartments formed thereby, and the top member 16 has a right angular flange 20 extending forwardly of the flange 18 thereof, so as to comprise the only forwardly extending flange of the frame for a purpose to be later described. A right angular bracket 21 defining the oven and broiler compartments is disposed across the front frame member and fastened to the rearwardly extending flanges 19 of the side members, upright

flange portion 22 of the bracket being adapted to be in the same plane as flanges 17 and 18 of the side and top members of the frame.

Referring now to Figure 1, doors 23 and 24 are mounted on faces 17 of the side members, so as to form the front enclosure for the respective oven and broiler compartments. Metallic sheets coated and finished as with enamel or the like are provided for the top of the oven compartment as at 25 and the sides of the oven and broiler compartments as at 26, the sheet on the side furthest away in the drawing not shown being the same in its assembly and disposition as the side sheet 26 shown in the drawing.

15 It is to be noted that the doors 23 and 24 when in closed position substantially cover the flanges 17 of the side members and flanges 18 and 22 respectively of the bracket members, all of which flanges are in the common plane as 20 heretofore described.

Referring now to Figure 1, it is to be noted that sheets 25 and 26 covering respectively the top and sides of the oven and broiler compartments are so disposed as to terminate adjacent 25 to the edges respectively of the forwardly projecting flange 20 of the top member and the flanges 17 of the side members, thereby to expose, when the stove is assembled in the manner shown in Figure 1 with the doors 23 and 24 of the broiler 30 compartment closed, an enclosure in which are exposed only the extreme edges of the forwardly extending flange 20 of the top member and the edges of the flanges 17 of the side members, which flanges need not be enamelled but which 35 edges form beads which, when painted black, will provide sufficient ornamental effect, and at the same time produce the necessary structural rigidity required for maintaining the sheets in position.

40 Further, as may be noted from Figure 1, the door 23 of the oven compartment has its upper surface in contact with the under surface of flange 20, thus while the peripheral front edges thereof contact with the surfaces 17, and 18, 45 and 22 of the flanges in the common plane of the side, top and bracket members, thereby eliminating the tendency and possibility of escape of heated air or vapors from the interior of the oven compartment when the stove is in 50 operation.

Referring to Figure 3, the frame section has associated therewith, in conjunction with metallic sheet 26, a metallic sheet 27 serving as an inner lining for the compartment; the said sheet 27 being offset at its front end portion as at 28 as to permit the exterior face of such sheet to rest against the outer portion of flange 19, and also to cause right angular portion 29 adjacent the offset portion 28 to rest against the edge 60 of the flange 19, thus eliminating the use of bolts for the interior lining.

Although no insulation is shown between sheets 26 and 27, it is within the province of this invention to so construct the compartment 65 as to provide, if desired, for insulation between such sheets.

It is obvious that various changes and modifications may be made to the details of construction without departing from the general spirit of the invention as set forth in the appended claims:

We claim:

1. In a gas range having an oven compartment, a vertical front frame defining an opening to 75 said compartment, each of the elements of said

front frame having one flange in a common plane, and a door carried on said front frame and adapted to substantially cover all of the flanges in the common plane thereof when closed, the top element of said front frame having one flange extending outwardly above said door, said flange being the only portion of the respective elements projecting forwardly of the common plane, and metallic sheets adjacent to and carried by said frame forming the top and sides of the oven compartment, said sheets being so disposed as to expose only the outside edge of the side and top elements, and the ends of the top element.

2. In a gas range having an oven compartment, a front frame forming an opening to said oven compartment, metallic sheets forming top and sides defining said compartment, said front frame being constructed of members each of which has one surface in the common plane, the top member of said frame having a flange extending forwardly of the frame and the side members of the frame having flanges extending rearwardly thereof, the top and side members of the frame all having one surface in a common plane, a door carried on said front frame being adapted to substantially cover all the flanges in the common plane thereof when closed, said metallic sheets when assembled and the door when closed being adapted to expose only the side edges of the surfaces of the side members in the common plane and the front edge of the flange extending forwardly of the top member of the frame.

3. In a gas range having a sheet metal oven compartment, a front frame defining an opening to said compartment, each of the elements of said front frame having one flange in a common plane, and a door carried on said front frame and adapted to substantially cover all of the flanges in the common plane thereof, the top element of said frame having one flange projecting outwardly above said door, said flange being the only portion of the respective elements projecting forwardly of the common plane, the side elements of said frame each having one flange extending inwardly into said compartment in a plane nearest the center line of the frame, and metallic sheets forming the side enclosure for said oven compartment carried by the side elements of the frame, all of the frame but the side edges of the side members and the edge of the forwardly projecting top member being concealed when the door is in the closed position.

4. In a gas range, a front frame defining an opening for an oven compartment, each of the elements of said front frame having one flange in a common plane, a door carried on said front frame and adapted substantially to cover all the flanges in the common plane thereof, the top element of said frame having one flange extending forwardly above said door, the side elements of said frame having flanges projecting inwardly into said compartment in planes near the center line of said compartment, metallic sheets having a finished surface on the outer surfaces thereof, disposed along the top and sides of the frame to enclose the compartment, said sheets extending to the edges of the flanges of the side elements in the common plane and to the edge of the forwardly extending flange of the top element, thereby to expose when the door is in closed position only the edge of the forwardly extending top flange and the edges of the side elements in the common plane of the front frame.

5. In a gas range having a stove side and an oven side, said oven side comprising an oven compartment and a broiler compartment therebelow, a frame defining openings for said compartments, each of the elements of said frame having one flange in a common plane, the top element of said frame having a flange projecting outwardly and the side elements of said frame having flanges projecting inwardly into 10 said compartments in planes near the center of said compartments, doors for said compartments carried on said frame and adapted substantially to cover all the flanges in the common plane of said frame, sheets forming top and sides for said 15 compartment and carried by said frame elements to form enclosures for said compartments, the said sheets being so disposed as to expose only the outside edges of said side elements and the forward edge of said top element of said 20 frame when the doors for the compartments are in closed position. 25
6. In a stove having an oven compartment, a front frame defining an opening to said oven compartment, said front frame being constructed of angle-shaped members, each of which has one flange in a common plane, the top member having a flange extending forward of said common plane, and the side members each having a flange extending rearward of the common plane. 30
7. In a stove having an oven compartment, a vertical front frame defining an opening to said compartment, said frame being constructed of angle-shaped members, each of which has one flange in a common plane, a door carried on said 35 frame and adapted to substantially cover all flanges in the common plane when closed, the
- top member having a flange extending outwardly above said door, the side members each having one flange extending inwardly into said compartment, metallic sheets forming the inner sides of the compartment, the forward edges of said sheets being disposed adjacent the inwardly extending flanges of the side members. 80
8. In a stove having an oven compartment, a vertical front frame defining an opening to said compartment, said frame being composed of angle-shaped members, each of which has one flange in a common plane, the top member having a flange extending forwardly, the side members each having a flange extending rearwardly, 85 lining sheets forming the said compartments, said lining sheets being offset along their forward edges and so disposed that said forward edges lie adjacent one surface of said rearwardly extending flanges, while the inner surfaces of said lining sheets are approximately in the plane 90 of the opposite surface of the rearwardly extending flange. 95
9. In a stove with an oven compartment having a plurality of sheets disposed in spaced relationship and forming respectively the inner and outer sides of the compartment, a front frame constructed of angle-shaped members, each having one flange in a common plane, the side members each having one flange extending rearwardly of the common plane, the said outer side sheets being attached respectively to the frame on a flange in said common plane, and the said inner side sheets being held in position by said rearwardly extending flanges. 100
